(57) **CLAIM**

The ornamental design for the simulated eye for toys, as
shown and described.

DESCRIPTION

FIG. 1 is a front perspective view of a simulated eye for toys
according to my design;

FIG. 2 is a front view of my simulated eye for toys according
to FIG. 1;

FIG. 3 is a rear view of my simulated eye for toys according
to FIG. 1;

FIG. 4 is a left side view of my simulated eye for toys
according to FIG. 1;

FIG. 5 is a right side view of my simulated eye for toys
according to FIG. 1;

FIG. 6 is a top view of my simulated eye for toys according
to FIG. 1; and,

FIG. 7 is a bottom view of my simulated eye for toys
according to FIG. 1.
